SEPARATION OF TALL OIL INTO ITS CONSTITUENTS

John D. Jenkins, Milwaukee, Wis., assignor to
 Pittsburgh Plate Glass Company, Allegheny
 County, Pa., a corporation of Pennsylvania

Application December 19, 1941, Serial No. 423,627

2 Claims. (Cl. 260—97.5)

The present invention relates to the separation of tall oil into its components and it has particular relation to such separation when effected by means of a system of selective solvents.

One object of the invention is to provide a simple process of obtaining a fraction of fatty acids in high concentration from the resin acids in tall oil.

A second object of the invention is to provide a simple and convenient embodiment of apparatus for use in the practice of the invention.

These and other objects will be apparent from consideration of the following specification and the appended claims.

Tall oil results from the manufacture of paper pulp by the sulfate method and is obtained in amounts of thousands of tons annually. It comprises a mixture of components including large percentages of fatty acids and resin acids, together with some non-acid constituents, which include considerable amounts of sterols. The latter are highly valuable for use in the preparation of certain pharmaceutical materials.

The fatty acids are of such nature that, in sufficiently pure state, they would be of great value in the preparation of synthetic resins, soap stocks and the like. However, by reason of the presence of the resin acids, it has heretofore been impracticable to employ them to any appreciable degree, except in a few very cheap products. Therefore, the value of tall oil has always remained low.

The present invention contemplates the provision of a process whereby large percentages of free fatty acids can be separated in comparatively pure form from the resin acids while the resin acids in turn are obtained in a comparatively concentrated state.

For a better understanding of the invention reference may now be had to the accompanying drawing in which Figs. 1 and 2 illustrate diagrammatically convenient embodiments of the invention.

In the drawing like numerals refer to like parts throughout.

The apparatus as shown includes an extraction column 10, which may be of conventional design and preferably includes a packing or Raschig rings, or other suitable material designed to promote complete and thorough intermingling of liquids passing through the column. A selective polar solvent having an affinity for resin acids is passed into the top of the column as indicated at 11. This solvent may comprise an aqueous

solution of the monomethyl ether of ethylene glycol, furfural, or diacetone alcohol or any one of a number of polar solvents, which tend selectively to dissolve resins in tall oil. The concentration of water in the solvent should not be too high. For example, in the case of the monomethyl ether of ethylene glycol it should be within the approximate range of 8 to 12 per cent. In the case of furfural, it probably should be about 2 to 4 per cent. In the case of diacetone alcohol the ratio of water should approximate 11 per cent.

Tall oil to be extracted in the column may be stored in a container 12 and naphtha or the like hydrocarbon solvent, having a preference for fatty acids and being immiscible with the polar solvent, may be stored in a container 13. The tall oil and the naphtha are discharged through lines 14 and 16 into a common line 17 where they are intermingled, then discharged into the base portion of the column 10 where they flow concurrently to each other and counter-currently to the polar solvent.

A first raffinate highly rich in fatty acids and containing a considerable proportion of the non-acid constituents all dissolved in the naphtha are discharged at the top of the column as indicated at 18. The first extract comprising the selective polar solvent and the major portion of the resin acids, as well as some of the fatty acids, is discharged as indicated at 19 from the base of the column. The extract, if desired, may be concentrated by evaporation of solvents in a still 21. However, this operation is optional and, if preferred, the extract may be passed through line 22 directly to a second column 23, which is fed near its bottom with a second portion of naphtha introduced at 24.

The extract from column 23 comprises a high concentration of resin acids and a considerable percentage of fatty acids. It is withdrawn as indicated at 26 near the base of the column. The second raffinate, comprising naphtha in which is dissolved an enriched portion of fatty acids and a small amount of resin acids, is drawn off at 27, near the top of column 23 and is returned as a back feed to the base of the column 10. If desired, it may be passed through a still 28, where it is substantially concentrated and then returned to the naphtha feed through a line 29. However, the concentration is not strictly required. If preferred, the complete raffinate may be recycled without concentration. Where the second raffinate is concentrated, the purified or

partially purified naphtha from the still 28 is returned through the line 18 to naphtha storage in container 18.

Raffinate from column 18 may be fed optionally with or without being concentrated in still 33, to the base of a third column 34, where it is counter-currently washed with a wet polar solvent introduced as indicated at 36 at the top. The third raffinate, highly rich in fatty acids and non-acids, passes out as indicated at 37 near the top of the column 34 while the extract comprising the wet polar solvent together with a concentration of resin acids and a portion of fatty acids and non-acids is drawn off as indicated at 38 near the base.

In the operation of the apparatus the various extractions may be conducted approximately at room temperatures though temperatures 10 or 20 degrees higher or lower may optionally be employed in some cases. The ratios of the ingredients may be varied over considerable range. However, the following constitute specific examples of ranges which may be employed in case methyl cellosolve is employed as the polar solvent.

Column 10 may be fed at 11 with a mixture comprising 8 to 12 per cent of water in monomethyl ether of ethylene glycol. The proportion of solvent mixture may be approximately 4250 parts by weight. Approximately 126 parts by weight of tall oil from container 12 and 379 parts by weight of naphtha or petroleum ether are intermingled and fed to the base of the column at 17. Approximately 1950 parts by weight of naphtha or petroleum ether are fed to the base of column 23 and approximately 1000 parts by weight of wet polar solvent may be fed in at the top of column 34. The raffinate from the third extraction will comprise a mixture of resins and fatty acids in which the ratio of fatty acids will be approximately 90 per cent and the resin acids will be approximately 10 per cent, based upon total acids content of the fraction. The extract will comprise fatty acids and resin acids in the approximate ratios of 43 and 57 per cent.

The extract can be used in certain soap stocks, or otherwise worked up or utilized. The raffinate is valuable for use in resin manufacture and other purposes.

A slightly modified embodiment of apparatus suitable for use in the practice of the invention is disclosed in Fig. 2. This apparatus includes a column 40 designed to receive a feed of tall oil and naphtha or other suitable hydrocarbon at an intermediate point, e. g., approximately the middle, as indicated at 41. A polar solvent medium, such as aqueous monomethyl ether of ethylene glycol is fed into the system at or near the top of the column at the point indicated by the arrow 42. Naphtha for absorbing and carrying away the fatty acids of the tall oil mixture is introduced near the base of the column as indicated at 43. The extract is also drawn off at the base, preferably slightly below the point of introduction of the naphtha, as indicated at 44.

The raffinate phase comprising primarily a concentrate of free fatty acids in naphtha passes out through line 47 and is fed into the base portion of a second column 48 and flows counter-currently upwardly through a second wash of aqueous polar solvent introduced at 49. A second extract is taken off at the base of the second column as indicated at 51 while a second raffinate

is taken off near the top of the column, as indicated at 52.

It will be apparent that the operation of this apparatus is very similar to that disclosed in Fig. 1, where the latter is operated without removal of solvent between stages. The upper portion of the column 40 acts substantially as the column 10 of Fig. 1 and the lower portion behaves as the column 23 in which the extract phase from the top of the column is rewash with hydrocarbon.

It will be apparent that the extracts from either of the columns and the raffinate from the column 48 can be drawn off for further treatment. For example, the second raffinate from the outlet 52 includes free fatty acids and a relatively high percentage of sterols which can be separated from each other by combination of chemical and extraction steps. For example, the raffinate phase may be distilled to eliminate the solvent medium after which it can be treated with aqueous alkali, such as sodium or potassium hydroxide to saponify the free acids. The sterols can then be extracted from the acids by means of a suitable solvent, such as ether. The fatty acid after saponification can, if desired, be further treated in order to obtain conjugate and non-conjugate portions therefrom. Such process is disclosed in my copending application Serial No. 423,623, filed December 19, 1941, and entitled Treatment of tall oil.

The process broadly involves hydrolyzation of the soaps followed by esterification and further extraction with a selective solvent system, such as simultaneous extraction with furfural, or ethyl acetoacetate and petroleum naphtha. Such treatment results in separation of a fraction exceptionally rich in non-conjugate acids, which fraction is well adapted for use as a modifier in alkyd resins.

The extract phases from outlets 44 and 51 can also be treated for purposes of removing free resin acids from the fatty acids. A convenient process for this purpose is disclosed in my copending application entitled Refining of tall oil, Serial No. 423,626, filed December 19, 1941. It involves the addition of water to the extract phases, in order to bring the water content up to the point at which the resin acids will tend to crystallize out. In the case of methyl ether of ethylene glycol this is conveniently effected when the solvent medium contains about 24 per cent of water. The resin acids then crystallize out and can be recovered.

Of course, if desired, the removal of the resin acids by crystallization can be stopped at a convenient point, for example, when the concentration of the resin acids to fatty acids is approximately the same as that in the original tall oil. The crystals can be removed from this solution, the solvent evaporated and the tall oil recycled to column 40 along with additional tall oil. The various phases from the outlets 51 and 52 can also be separated from the solvents, for example, by a vacuum evaporation and are then suitable for industrial applications. For example, the resin action fraction can be employed as a stock for certain soaps, while the fatty acids can be used as modifiers for artificial resins, soap stocks and other industrial applications.

The preliminary admixture of the tall oil with the tall oil fed into the extraction columns with naphtha has been described. It will be apparent that it could also be admixed with the initial feed of polar solvent. For example tall oil admixed

with wet solvent could be fed into columns 10 or 40 through lines 11 and 42.

The forms of the invention herein shown and described are to be considered merely as exemplary. It will be apparent to those skilled in the art that numerous modifications can be made therein without departure from the spirit of the invention or the scope of the claims.

What I claim is:

1. A process of separating tall oil into useful fractions, one being substantially enriched in resin acids and correspondingly impoverished in fatty acids and the other being substantially enriched in fatty acids and impoverished in resin acids, which process comprises admixing tall oil with a liquid hydrocarbon solvent, flowing it through a first zone countercurrently to and in contact with a mixture of water and a water miscible polar solvent which has a relatively high affinity for the resin acids and a lesser affinity for fatty acids and is insoluble in the hydrocarbon solvent and simultaneously subjecting the extract phase from the first zone to countercurrent washing in a second zone with a liquid hydrocarbon solvent having a relatively high affinity for fatty acids, the polar solvent exceeding the hydrocarbon in volume, flowing the hydrocarbon solvent used in said washing operation through the first zone, withdrawing a phase comprising the hydrocarbon solvent and the acids dissolved therein from the first zone and further extracting the last mentioned phase with additional polar solvent in a third zone to obtain two additional phases, one comprising hydrocarbon saturated with said fraction of fatty acids impoverished in resin acids and the other comprising hydrocarbon saturated with a fraction rich in resin acids and poor in fatty acids.

5 with said useful fraction of fatty acids impoverished in resin acids and the other comprising the polar solvent saturated with a fraction rich in resin acids and poor in fatty acids.

2. A process of separating tall oil into useful fractions, one being substantially enriched in resin acids and correspondingly impoverished in fatty acids and the other being substantially enriched in fatty acids and impoverished in resin acids, which process comprises admixing tall oil in a ratio of about 126 parts by weight with a liquid hydrocarbon solvent through a ratio of about 379 parts by weight, flowing it in a first zone countercurrently to a mixture of monomethyl ether of ethylene glycol and water in a ratio of about 4250 parts by weight and simultaneously subjecting the extract from the first zone to countercurrent washing in a second zone with a liquid hydrocarbon solvent in a ratio of about 1950 parts by 15 weight having a relatively high affinity for fatty acids and lesser affinity for resin acids, flowing the hydrocarbon solvent used in said washing operation through the first zone, withdrawing a phase comprising the hydrocarbon solvent and the acids dissolved therein from the first zone and further extracting the solution with additional monomethyl ether of ethylene glycol in a third zone to obtain two additional phases, one comprising hydrocarbon saturated with said fraction of fatty acids impoverished in resin acids and the other comprising the monomethyl ether of ethylene glycol saturated with a fraction rich in 20 resin acids and poor in fatty acids.

JOHN D. JENKINS.
